UNITED STATES PATENT OFFICE.

ELLIOT SAVAGE, OF WEST MERIDEN, CONNECTICUT, ASSIGNOR TO THE
SAVAGE FURNACE COMPANY, OF SAME PLACE.

METALLURGICAL FURNACE.

SPECIFICATION forming part of Letters Patent No. 228,944, dated June 15, 1880.
Application filed November 11, 1879.

To all whom it may concern:

Be it known that I, ELLIOT SAVAGE, of West Meriden, in the county of New Haven and State of Connecticut, have invented a new and useful Improvement in Metallurgical Furnaces, 5 of which the following is a specification.

The object of this invention is a metallurgical furnace in which the combustion of the fuel can be perfectly controlled, so that the 10 nature or character of the flame admitted to the heating-chamber may be made, as desired, either a reducing-flame or an oxidizing-flame, according as the duty to be performed in the heating-chamber requires one or the other.

15 The invention consists in a peculiar arrangement of a coking, a fuel, and a heating chamber, and a flue or flues uniting said fuel and heating chambers, combined with one or more air-passages which are controlled by suitable 20 valves, by which the supply of air to the fuel-chamber and to the gases passing from the fuel to the heating chamber may be perfectly controlled.

It further consists in an arrangement of 25 flues through which the gases which pass from the heating-chamber are returned to a second combustion-chamber, which chamber is located beneath the flue which conveys the gases from the fuel-chamber and adjacent to the passage 30 which admits air to said gases. The flues from the second combustion-chamber pass around the flue that conveys the gases to the heating-chamber, so that the heat produced from the perfect combustion of the gases in the second 35 combustion-chamber is utilized to heat the air supplied to the gaseous fuel entering the heating-chamber as well as the gases with which it combines.

In the accompanying drawings, in which 40 like letters of reference indicate identical parts in the various figures, Figure 1 is a central longitudinal vertical section of a furnace embodying my improvements. Fig. 2 is a transverse vertical section taken through line 45 *a a* of Fig. 1. Fig. 3 is a horizontal sectional plan view taken in line *b b* of Fig. 1. Fig. 4 is a similar view taken in line *c c*; and Fig. 5 is a plan taken in section on line *d d* of Fig. 1.

The walls or mason-work of the furnace are 50 represented by letter A.

B is the coking-chamber, having an inclined dead-plate, upon which the fuel is thrown. This is shown located above the grate in front of the furnace; but it may, if desired, be located upon either side of the fuel-chamber C, 55 or one upon each side.

D is a flue leading from the fuel-chamber C to the heating-chamber E.

F G are flues which pass down at the rear corners of the heating-chamber and return 60 upon each side below the heating-chamber. Through these flues the gases pass from the heating-chamber to the second combustion-chamber, G.

H I are flues leading from the second combustion-chamber around flue D and into the uptake I.

J is an air-passage opening into a narrow chamber, K, in the rear wall of the fuel-chamber, and L is an air-passage in rear of the 70 ash-pit M. L l l are perforations passing from this passage to the ash-pit, for the purpose of admitting air to the fuel through grate-bars N, and O is the air-passage to admit air to the second combustion-chamber through the narrow 75 chamber P. The air-passages are each fitted with a valve or wind-gate, Q, and a short pipe, R, to connect with the pipe of a fan or blower.

S is the door of the coking-chamber, and T the door of the heating-chamber. 80

Inspection-openings are provided in the walls of the chamber, through which the operator may observe the flame and determine the amount of atmospheric oxygen to be admitted to produce the required flame in the heating- 85 or smelting chamber, which will, of course, depend upon the character of work required of the furnace.

The character of the flame, as well as its intensity, is regulated or changed at will by regulating the supply of atmospheric oxygen admitted through the ports J and L l l. If an oxidizing-flame is required in the heating-chamber, a sufficient quantity of oxygen is supplied, through port J, to the gaseous fuel 95 and carbonic oxide passing from the fire-box to flue D to unite with the carbon in the gases and produce carbonic acid.

The intensity of the flame may be regulated with perfect exactness. If but a moderate 100

heat is required, less air is admitted through the ports J and L; if an intense heat is required, a full blast is introduced through these ports; if a reducing or carbonizing flame is required, 5 the supply of air admitted through port J is limited until the proper effect is produced. I am thus enabled to produce the various grades of iron or steel from the same ore.

The gases, after passing from the heating or 10 smelting chamber E to the second combustion-chamber, G, through flues F, receive sufficient air through port O to combine with any carbon remaining in the gases, thus producing perfect combustion and utilizing the heat 15 thus generated to heat walls of flue D and the walls of the air-chambers K P.

The changes of form necessary to adapt my furnace to the various requirements of smelting, heating, annealing, or forging will be 20 readily understood by those skilled in the art, and need no description here.

Having thus described my invention, I claim—

1. In a metallurgical furnace, the combination of the chambers B, C, and E with flue 25 D and an air-port controlled by a valve for

the admission of air to the gases at the junction of said chamber C and flue D, for the purpose specified.

2. In a metallurgical furnace, the combination of the chambers B, C, and E with flue 30 D, port J, to admit air to the gases at the junction of chamber C and flue D, and port L, to admit air under the grate, said ports J and L having valves Q, substantially as specified.

3. The combination, substantially as specified, of the chambers B, C, E, and G, flues D and F, with the air-passages J, L, and O, and their controlling-valves Q.

4. In a metallurgical furnace, the combination, substantially as specified, of flue D, chamber G, flues H H, and air-chambers K and P, said flues H H passing upon the sides of flue 45 D, and said chamber G being in close proximity to chambers K and P, for the purpose specified.

ELLIOT SAVAGE.
